FOLDING BED DAVENPORT

Atcheson V. Hartford, San Francisco, Calif.

Application March 20, 1935, Serial No. 12,023

3 Claims. (Cl. 5—16)

My invention relates to improvements in folding bed davenport's wherein folding bed sections are folded within a back-well of a davenport body and are arranged to be extended to form a bed spring to support a top mattress in operative or unfolded position, one of said sections carrying the back cushion of the davenport in such a manner that the same will not interfere with a comfortable occupancy of the bed when extended, and wherein one of the supporting legs for supporting said sections in extended position may be used as a handle to facilitate folding and unfolding of said sections.

The primary object of the present invention is to provide an improved folding bed davenport.

Another object is to provide a new and improved folding bed davenport of simple and efficient construction and arranged to support folding bed sections, when extended, at a regulation bed height and which may be easily folded and concealed within a davenport when folded, without betraying the nature of the davenport.

A further object is to provide a new and improved device of the character set forth having improved and simplified means for preventing the sagging along a central longitudinal line of a double bed whereby said bed may be comfortably occupied by two persons.

A still further object of the present invention is to provide a support or leg for one of the folding sections which may be used as a handle to facilitate movement of the folding sections into and out of the davenport body and which may be easily concealed and yet readily accessible when required for use.

I accomplish these and other objects by means of the improved device disclosed in the drawings forming a part of the present application, in which—

40. Fig. 1 is a transverse sectional view of a davenport body with my improved folding bed sections in folded position therein;

Fig. 2 is a similar view disclosing the folding bed sections partly unfolded;

45. Fig. 3 is a similar view disclosing the bed sections fully extended and supported at regulation height;

Fig. 4 is a broken plan view of the bed in extended position;

50. Fig. 5 is a detailed transverse sectional view taken on line 5—5 of Fig. 3, in the direction indicated; and

Figs. 6 and 7 are enlarged broken detailed views disclosing one of the joints between the folding bed sections.

Referring to the drawings:

The numeral 1 is used to designate in general a davenport body having the usual arms 2, wings 3, back 4, and the usual seat cushion supports 6 for supporting the removable seat cushions indicated in dotted lines at 7, in Fig. 1 of the drawings.

The seat cushion supports 6 are placed in the forward or front portion of the body 1 so as to form a substantially vertically disposed well or compartment 8 within which is a pair of straps 9 bent U-shaped to support the folded sections.

The folding bed sections comprise a central section 11, a head section 12, and a foot section 14, hingedly connected together in the usual manner, the central section 11 and foot section 14 being hingedly connected by a short intermediate section 16, the purpose of which will hereinafter be more fully set forth.

The central section is provided with a pair of 20 forwardly extending arms 17, one on each side thereof, the free ends of said arms 17 being pivotally mounted upon the inner sides of the arms 2 of the body 1 and between said arms 2 and the ends of the removable seat cushions 7 thereon. 25 As these seat cushions form no part of the present invention, they are merely indicated in dotted lines, being the usual removable seat cushions common to most folding bed davenport's.

The folding bed sections 11, 12, 14 and 16 are 30 preferably composed of angle iron and have stretched thereon suitable spring mattress members 18, as disclosed in Fig. 4 of the drawings. The several sections are also properly reinforced by the bent transverse braces 19 to impart sufficient rigidity to the supporting structure for the spring mattress members 18.

The back cushion 21 of the davenport 1 is attached at its lower edge to the central section 11 by means of flexible metal straps 22, and at 40 its upper end by double hinged members 23 to the foot section 14, as disclosed in Figs. 1, 2, and 3 of the drawings. The top of the back cushion 21 has an angular extension 24 to the end of which is hingedly connected, by one of 45 the double hinges 23, a cushioned flap or extension 26, by means of which hinged connection said flap or extension 26 may drop away from the under side of the sections when extended, so as not to interfere with a comfortable occupancy of the bed.

An inverted U-shaped supporting leg or foot 27 has its upper ends pivotally mounted upon opposite sides of the central section 11, while its connecting portion or member rests upon a floor, 55

the foot or support 27 being of such length that it will cooperate with the pivoted arms 17 to support the central section 11 horizontally when the sections are extended, as disclosed in Figs. 5 3 and 5 of the drawings. This foot is preferably covered with a suitable fabric to match the fabric of the body 1 to provide a comfortable grip for the hands when used as a handle in opening or closing the bed in a manner hereinafter more 10 fully set forth.

The outer end of the foot section 14 is provided with a pair of supports or legs 28 pivotally connected thereto by a pair of rods 29 of different length or radius so that when said legs are 15 folded they will lie flat on the under side of the foot section 14, as disclosed in Fig. 1 of the drawings.

The intermediate section 16 is provided with a secondary angle 31 secured therein, said section 20 16, as well as the angle 31, is provided with square abutting shoulders 32 which abut with similar shoulders 32 upon the ends of the adjacent central and foot sections 11 and 14 respectively. By means of this arrangement, the movement of the several sections about their connecting pivotal points is limited in order to maintain the several sections in horizontal alignment when extended. The same square shoulders 32 are provided at the pivotal or hingedly connected 25 junction of the central and head sections 11 and 12 respectively.

A suitable spring 34 is connected on each side of the central section 11 and to the back 4, the tension of which acts as a counterbalancing force 30 to check the final closing as well as the final extension movement of the folded sections.

In order to prevent undue sagging of the spring mattress members 18 when the bed is occupied by two persons, I have provided a non-stretchable member or chain 36 longitudinally and centrally of the several extended sections, as disclosed in Fig. 4 of the drawings. This chain or member 36 has been purposely omitted from the other figures of the drawings in order to 45 close the more important parts which it would, in such folded positions, tend to obscure.

In operation the removable seat cushions, indicated in dotted lines in Fig. 1 of the drawings, are first removed and the leg or support 27, the lower end of which rests along the lower portion of the back cushion 21, is then exposed and rendered accessible for use, the legs of the same resting between the ends of the back cushion 21 and the wings 3 50 of the body 1. The support 27 is then moved outwardly or forwardly as disclosed in dotted lines in Fig. 1 of the drawings, and then serves as a handle by means of which the several folded sections may be pulled out into 55 operative or extended position, the counterbalancing effort of the springs 34 readily absorbing a portion of the weight of said folded sections.

As the central section 11 moves to a horizontal 60 position, the leg or support 27 is released, and actuated by the attraction of gravity, swings upon its pivots upon the central section 11 until it assumes a vertical position disclosed in Fig. 3 of the drawings, thereby supporting said central section 11, in conjunction with the arms 17, in a horizontal position.

When the central portion or section 11 is horizontal, the foot portion 14 is next unfolded or moved to a horizontal position. As the square abutting shoulders 32 between the central, inter-

mediate and foot sections 11, 16, and 14, respectively, abut, the said intermediate section 16, as well as the foot section 14, will be supported in said horizontal position by said abutting shoulders. The horizontal position of these several sections is further supported by the leg 28 which is moved upon its arms 29 to assume an operative supporting position.

The bed is then ready for occupancy.

If it is occupied by two persons, sleeping, in the usual manner, on opposite sides of said extended sections, the non-stretchable chain or member 36 will prevent undue sagging of the spring mattress members 18 at the center and thereby prevent said two occupants from rolling together into the center of the extended sections.

When the parts are extended, the back cushion 21, being connected by the flexible straps 22 and the double hinges 23, will be permitted to move away from the bottom of the extended central section 11, as disclosed in Fig. 3 of the drawings, a sufficient extent to allow a comfortable movement of the spring mattress members 18 and thereby prevent contact with an occupant of said extended sections.

The several sections may be readily folded back into the body 1 of the davenport by reversing the above described opening or extending process.

When the sections are being folded into the body 1, the tension of the springs 34 again acts as a counter-balancing force to absorb a portion of the weight of the folding sections, thereby facilitating the closing as well as the opening operation.

When the folded parts have been lowered into position within the body 1, the handle or support 27 is again lowered with its legs pressed back and concealed between the ends of the back cushion 21 and the wings 3 of the body 1. When the removable seat cushions, indicated at 7 in Fig. 1 of the drawings, are replaced they totally conceal the lower or connecting portion of said member 27.

Having thus described my invention, I claim—

1. A folding bed davenport comprising a davenport body having a compartment back of the seat and back cushions, and extending from the top of the bottom of said body; a folding bed frame comprising hinged central head and foot sections folded within said compartment; laterally extending arms mounted upon each side of the central section and having their free ends pivotally mounted upon the body between the seat cushions and the arms of said body to support the folding bed sections when extended, at regulation height above a floor; and a U-shaped supporting leg having its free ends pivotally connected to the sides of the central section and arranged to support said central section when extended and to lie between the ends of the back cushion and wings of the body and behind the seat cushions when folded, said support being arranged to be extended on its pivot forwardly of the back cushion to serve as a handle to facilitate the extending and folding of the folding sections.

2. A folding davenport bed comprising a body having arms, wings, and seat cushion supports arranged in spaced relation to the back of said body; a folding bed frame comprising hingedly connected head, central and foot sections folded between the cushion supports and the back of said body, said central section being substantially vertical; a davenport back cushion mounted upon the central section; forwardly extending arms mounted one upon each side of the central sec-

- tion and having their free ends pivotally mounted upon the inner sides of the body arms and arranged to support the folding bed sections, when extended, at a regulation height above a floor; and a U-shaped supporting leg having its free ends pivotally connected to opposite sides of the central section and arranged to support said section horizontally when extended and to lie between the ends of the back cushion on the central section and the body wings and back of removable seat cushions on the cushion supports when said sections are folded, and also arranged to be extended forwardly on its pivot to facilitate folding and extending of the bed sections.
5. A folding davenport bed comprising a body having arms, wings, and seat cushion supports arranged in spaced relation to the back of said body; a folding bed frame comprising hingedly connected head, central and foot sections folded between the cushion supports and the back of said body, said central section being substantially ver-
- tical; a davenport back cushion mounted upon the central section; forwardly extending arms mounted one upon each side of the central section and having their free ends pivotally mounted upon the inner sides of the body arms and arranged to support the folding bed sections, when extended, at a regulation height above a floor; a U-shaped supporting leg having its free ends pivotally connected to opposite sides of the central section and arranged to support said section horizontally when extended and to lie between the ends of the back cushion on the central section and the body wings and back of removable seat cushions on the cushion supports when said sections are folded, and also arranged to be extended 15 forwardly on its pivot to facilitate folding and extending of the bed sections; and a pair of straps secured between the seat cushion supports and the back of said body to support the weight of the folded sections. 20
